PET LITTER RETRIEVER

William L. Schmieler, 19609 Winslow Road,
Cleveland, Ohio 44120

Filed Apr. 23, 1973, Ser. No. 353,548

Term of patent 14 years

Int. Cl. D30—99

U.S. Cl. D30—99

FIG. 1 is a top plan view of a pet litter retriever showing my new design, the upper part of the handle being removed for convenience of illustration;

FIG. 2 is a reduced scale right side elevational view; and

FIG. 3 is a reduced scale front elevational view, a portion of the handle being omitted for convenience of illustration.

I claim:

The ornamental design for a pet litter retriever, as shown and described.
